UNITED STATES PATENT OFFICE

2,578,401

CAN OPENER

Joseph C. Cunningham, Baltimore, Md.

Application February 27, 1947, Serial No. 731,185

2 Claims. (Cl. 30—3)

1

This invention relates to can openers and more particularly to those intended for manual or motor powered use.

It is an object of the present invention to provide a new and improved can opener that will avoid one or more of the advantages and limitations of the prior art.

Another object of the invention is to provide a can opener that will remove portions of the container, it is used on, in a manner that will avoid the sharp cutting edges that conventional forms of can openers make.

Another object of the invention is to provide a can opener that will open a can without allowing any parts of the opening device to enter the can during the opening.

Other objects of the invention will become apparent as the invention is more fully set forth.

In the drawings:

Figure 1 is a side view of a can opener embodying this invention with portions broken away to indicate its interior structure;

Figure 2 is a plan view of Figure 1, and

Figure 3 is a sectional view of Figure 1, taken along line 3—3 of Figure 1.

Similar reference characters refer to similar parts throughout the drawings.

In the drawings provided with this application, a structure is provided by way of example to illustrate the principles of the invention, while the claims indicate the scope of the invention.

In this structure a frame 10 is formed hollow or open to permit the insertion of the works of a can opener mechanism. The mechanism consists of a shaft 11 journaled in the frame 10 and operated by a motor 12 of a manipulator handle 13 mounted thereon.

The shaft 11 carries a miter gear 43 that engages with an intermediate gear 14 of the same kind and meshes with another miter gear 15. This gear in turn operates shaft 22 which contains another miter gear 36. Miter gear 36 meshes with another miter gear 16. The shaft 17 on which the gear 16 is mounted supports a knurled wheel 18 that rotates clockwise (Fig. 3) and rides without slipping against the inner rim 19 of a can top to be opened by the device.

The intermediate gear 14 is on a shaft 20 that turns a milling cutter 21 that rotates clockwise (Fig. 3) and cuts into the material forming the outer peripheral surface of the rim 19. The shaft 20 is held in the frame structure 10 and turns in the same direction to that of the knurled wheel 18.

A shaft 22 supports the gear 15 and the shaft 17

2

supports the gear 16, all of which are mounted on the frame structure 10. The shaft 22 is splined to permit the gear 36 to travel on it adjustably in a horizontal direction. This permits the sliding frame 24 which independently supports the shafts 17 and 22 to be adjusted to varying thicknesses of the rim 19. The screw 25 enables the adjusting to be done effectively on the rod 38.

The container to be opened is supported on an adjustable bracket 26 attached to the frame structure 10 by the set screw 40 and is arranged with a ball bearing base plate 23 to allow the container 30 to rotate freely therewith, as the cutting mechanism 21 turns against its rim 19.

The object of the miller cutter 21 is to abrade the material of the rim rather than cut into it. The miller 21 cuts the material on its outside edge by abrading it and leaves the rib 19 with a smooth edge that is not apt to cut the hands and with its upper edge turned over so the cap can be replaced to cover the can and be removed easily by the hand of the user. Since the cutting is done on the outside of the bent rim of the can instead of into the can wall as is conventionally done, it allows the top of the can to be removed, as if it were a cover and prevent parts of the can or dirt from entering the can during the cutting operation. This permits the cover to be reused for covering the container many times if desired, a feature which the usual can opener does not anticipate.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. A can opener comprising a frame, a bracket adjustably mounted on said frame, means for rotatably supporting a container on said bracket, said container having a flanged closure, gearing carried by said frame, an abrading element driven by said gearing, said element being in contact with one side of the flanged closure, a knurled element also driven by said gearing, said knurled element being in contact with the opposite side of the flanged closure, and adjustable means for said knurled element to allow for the thickness of the flange closure.

2. A can opener as set forth in claim 1, the adjustable means for the knurled element including a shaft driving said knurled element, a

55

3

pair of gears driving said shaft, a housing for said gears and a sliding connection between said housing and said frame.
